UNITED STATES PATENT OFFICE.

CHARLES P. HOWARD, OF HARTFORD, CONNECTICUT, ASSIGNOR TO JAMES L. HOWARD & CO., OF SAME PLACE.

CAR-LAMP.

SPECIFICATION forming part of Letters Patent No. 224,434, dated February 10, 1880.

Application filed December 8, 1879.

To all whom it may concern:

Be it known that I, CHARLES P. HOWARD, of Hartford, in the county of Hartford and State of Connecticut, have invented a new and useful Improvement in Lamps for Railway-Cars and other purposes; and I do hereby declare that the following is a full, clear, and exact description of the same, reference being had to the accompanying drawings, forming part of this specification, in which—

Figure 1 is a vertical central section through the car-roof and lamp-jacket, showing the lamp-bowl with its attached burner and chimney in elevation, the ring of the bracket and interlocking ring of the lamp-bowl being also in section. Fig. 2 is a horizontal section on the line $x-x$ of Fig. 1. Fig. 3 is a vertical detail section, showing the fastenings of the uppermost portions of the lamp. Fig. 4 is a vertical section of a modification of my invention.

The object of my invention is to so construct a lamp that, in whatever way the currents of air exterior to the lamp operate with respect to the inlet and outlet openings and chambers or passages in communication with them, the resulting effect upon the column of hot air passing upward through the lamp shall be either to condense or rarefy the air of said column, accordingly as such operation of the external air tends to drive air into or draw air out of said openings and chambers or passages, and thus never materially accelerate or retard the velocity of its flow, which in practice is the only condition, under ordinary circumstances, influencing the steady burning of the light. In brief, the object of my invention is to prevent currents of air exterior to the lamp from injuriously affecting the hot-air column rising from the flame of the lamp, and to render the use of the lamp on wood car-roofs safe.

In the accompanying drawings, Figure 1, the three concentric tubes a , b , and c , inclosing and separating the spaces A , B , and C , together with the top g , flange i , and the deflecting-collar h , compose the smoke-jack.

The parts a , c , and h are fastened to the top g , as indicated at a^4 , c^4 , and h^4 , and the part b is formed with the flange i , or fastened to it,

and by means of this flange is attached to the car-roof R , together with the other parts of the smoke-jack, the tube a extending down to and resting also upon or being formed with the flange i . Thus the flange i , while covering a portion of the wood roof R , and guarding it from fire, supports the smoke-jack upon the roof in such a manner that the tubes b and c stand within the diameter of the draft-hole R^3 of the roof, as shown.

Around the upper edge of the tube a are openings r , communicating with the space A and the external air.

Between the upper edge of the tube b and the lower edge of the deflecting-collar h is an opening, s , communicating between spaces A and B . The deflecting-collar h makes a tight joint with the top g , so as to prevent air from passing directly from the opening t to the opening r , or the reverse—to wit, from r to t ; and the lower edge of this collar is flared outward for the purpose of deflecting cinders entering at r into the space A , and preventing them from entering through the opening s into the space B , whence they would fall into the car.

Z are holes in the outer tube, a , for the removal of cinders from the space A . Said holes might be provided with swinging or sliding doors to open and close; but in practice it has not been found necessary to do so.

Around the upper edge of the tube c the opening t , communicating between the spaces B and C , is only interrupted at intervals by the fastenings which unite the tube c with the top g . The tube c , at a point opposite the opening s , is enlarged by means of a bead, c' , rolled in it, or an outside collar, in order to deflect currents of air passing either down through space B or up through the same, and out through the opening s into the space A . The lower ends of the tubes b and c extend down into the hole R^3 a proper distance to surround and inclose two cylindrical tubes, d and e , which are connected together by a horizontal diaphragm, f' , and form an adjustable extension-chimney portion of the lamp-globe G .

The tubes d and e form the chambers or spaces D and F , and the tube d is attached to either the device patented October 17, 1876, by Frank L. Howard, as shown in Fig. 1, or a device

such as shown in Fig. 4, for adjusting this part of the lamp to a position for inserting or removing the globe G. If the device shown in Fig. 1 is adopted the collar l will be attached to the tube d, and slide longitudinally in the cylinder k toward and from the spring j, inclosed by the cylinder k and tube d. The spring, by bearing against the overhanging upper part of the cylinder k at one end and against the collar l at the other, presses the socket f firmly down upon the globe G, and thus holds the globe from lateral movement in its seat, formed around the lamp O by the shell or flange q of the lamp-supporting bracket-ring R². With this mode of confining the globe the tube d and its attached part f can be raised by hand against the pressure of the spring j sufficiently high to allow the globe to be removed from the lamp, and when the globe is removed the tube is caused to descend until its upper flanged end, d', strikes the upper end of the cylinder k, when it is arrested.

The tube b is fitted loosely within the upturned cylindrical portion W' of a broad circular plate attached to the inside of the car-roof R, and the cylinder k is supported upon a broad concave circular plate, W, which covers the flange of the portion W', and fastens to the under side of the car-roof, as shown.

The cylinder k is provided with a screw-threaded ring or collar, u', which screws into an internally-threaded screw-collar, u, securely attached to the plate W. Each of these screw-collars u and u' is provided at its lower end with a flange, and between these flanges the reflector Y is securely held.

By having the short cylindrical portion W' extend up into the hole R³ in the car-roof any sparks dropping through the space B are prevented from coming in contact with the wood-work of the roof R.

The parts q, f, d, and W are, respectively, perforated, as indicated at p, o, n, and m, the openings p communicating between the space Q and the air exterior to the lamp O, the openings o communicating between the space F and the air exterior to the lamp, the openings n communicating between the space D and the air exterior to the lamp, and the openings m communicating between the space B and the air within the car, exterior to the lamp.

The tube e is placed within the tube d, and arranged to extend down below the tube d, but not so high up as the same. This tube is of considerably less diameter than the tube d, and, by being connected to the tube d by means of the horizontal diaphragm f', the space between the tubes d and e is divided into two independent sections, D and F, and the air-openings n and o are compelled to supply air to the respective sections of said space independently of each other.

The lamp-bowl O, with burner N and glass chimney M, is fitted, by means of a ring with fastening-lugs, to the ring R² of the bracket R', which is suspended from the roof of the car.

Operation: The space A, the opening s, and

the space B form a continuous passage, opening at r into the air outside of the car, and at m into the air inside of the car, through which air can pass in either direction (according as the density of the exterior air is alternately greater or less than that within the car) without passing through any other portion of the lamp. The column of hot air discharged from the burner passes from the space P, inclosed by the glass globe, upward through the space E, inclosed within the smoke-pipe, into the space C, inclosed within the smoke-jack. Now, any disturbance in the air exterior to the lamp will act upon the column of air inclosed within the space P E C only through the openings p o n, the other two openings, m and r, being so related to each other that they mutually act to prevent the air entering through either from having much influence upon the current of hot air discharged into the space B through the opening t, and each of said openings p o n, being situated in the circumference of a vertical cylinder, will be acted upon alike by an identical current of air, and being located comparatively near each other will be acted upon in the same way, and to nearly the same degree, by a current of air blowing across the lamp. Now, as the opening p communicates through the space Q with the lower portion of the said column of air, and the opening o communicates through the space F with the middle portion of said column, and the opening n communicates through the space D with the upper portion of said column, it follows that all parts of said column of air are acted upon alike by any current of air exterior to the lamp, and either a condensation or rarefaction of the air composing it produced, and not a variation of its rate of flow; and as the lower portion of the tube e forms a shield to deflect the air passing through the opening o downward toward the lower portion, P, of said column, the indirect effect of the air passing through openings m and t and passages B B upon the upper portion of said column is thereby balanced and neutralized.

The modified plan of the lamp shown in Fig. 4 operates substantially as above set forth, and it only differs therefrom in some details of construction, to wit: The plate W is enlarged to form the reflector, thus dispensing with the reflector Y and screw-collars u u'. The spring globe-holder shown in Fig. 1 is substituted by a clamp or catch, X, attached to the neck of the plate W, through which the tube d loosely passes, arranged so as to hold the tube d, and therefore the socket f, down against the globe. The openings n in the tube d are closed, and the passages B B, together with the openings m and t, are depended upon to balance the effects of openings p upon the column of air P, E, and C, and the tube e, above its junction with the socket f, is dispensed with, as shown.

In lamps where the glass globe is cemented into the sockets formed by f and q the tube d is attached securely to the plate W, and said

plate is supported in place by the tube *d* and globe *G*, instead of being fastened directly to the roof.

The lamp as modified in Fig. 4, although inferior in its power to resist the influence of exterior currents of air to that plan represented in Figs. 1, 2, and 3, yet carries out the same general principle thereof to such an extent as to make it superior, in its resistance to said influences, to lamps heretofore constructed.

What I claim is—

1. The smoke-jack of a lamp, consisting of the concentric tubes *a*, *b*, and *c*, the top *g*, the deflecting-collar *h*, and the flange *i*, substantially as and for the purpose described.

2. The combination of the smoke-jack, consisting of three concentric tubes, *a* *b* *c*, the top *g*, and the deflecting-collar *h*, and the smoke-pipe, consisting of the two concentric tubes *d* and *e* and the globe-socket *f*, perforated around its circumference with the openings *o*, substantially as described.

3. The smoke-pipe of the lamp, consisting of the tube *e*, the concentric tube *d*, perforated around its circumference with the openings *n*, and the globe-socket *f*, perforated around its circumference with the openings *o*, substantially as and for the purpose described.

4. The supporting-plate *W*, perforated with the openings *m* around the central opening, *R*³, through which the smoke-pipe of the lamp passes, in combination with the said smoke-pipe, consisting of the two concentric tubes *d* and *e* and the globe-socket *f*, perforated around its circumference with the openings *o*, substantially as and for the purpose described.

5. The supporting-plate *W*, perforated with openings *m* around the central opening, *R*³, through which the smoke-pipe of the lamp passes, in combination with the said smoke-pipe, consisting of the tube *e*, the concentric tube *d*, perforated around its circumference with the openings *n*, and the globe-socket *f*, perforated around its circumference with the openings *o*, substantially as described.

6. The combination of the plate *W*, perforated with the openings *m* around the central opening, *R*³, through which the smoke-pipe passes, the smoke-pipe, consisting of two tubes, *d* and *e*, and the globe-socket *f*, perforated around its circumference with the openings *o*, and the smoke-jack, consisting of the tubes *a*, *b*, and *c*, the top *g*, the deflecting-collar *h*, and the flange *i*, substantially as described.

7. The combination of the plate *W*, perforated with openings *m* around the central opening, *R*³, through which the smoke-pipe passes, the smoke-pipe, consisting of the tube *e*, the concentric tube *d*, perforated around its circumference with the openings *n*, and the globe-socket *f*, perforated with the openings *o*, and the smoke-jack, consisting of tubes *a*, *b*, and *c*, the top *g*, collar *h*, and flange *i*, substantially as described.

Witness my hand, in the matter of my application for a patent on a railroad-car and other lamps, this 22d day of November, 1879.
